UNITED STATES PATENT OFFICE.

CHARLES Q. C. LEIGH, OF CHICAGO, ILLINOIS.

VENEER SHIPPING-CRATE.

1,222,638.

Specification of Letters Patent. Patented Apr. 17, 1917.

Application filed September 8, 1916. Serial No. 119,020.

To all whom it may concern:

Be it known that I, CHARLES Q. C. LEIGH, a citizen of the United States, and a resident of the city of Chicago, county of Cook, and 5 State of Illinois, have invented certain new and useful Improvements in Veneer Shipping-Crates, of which the following is a specification.

My present invention has relation to folding crates which may be readily assembled for receiving goods and for holding the same during shipment and handling, and which may be folded into a package of very much reduced size for return after the crate 15 has been emptied.

The particular object of my present invention is the provision of a crate which can be made entirely of what is known as "veneer," or thin strips of wood, without requiring 20 pieces of molding of heavier dimensions than the veneer to be manufactured and assembled therewith. As is well known, veneer, while being more pliable than heavier pieces of wood, is very tough and much less 25 liable to break, and my crate is therefore much stronger than the crates formed with strips of molding or beading. My crate also 30 is less expensive to make, as it does away with the expense of the heavier molding strips.

I secure the above objects by means of the structure illustrated in the accompanying drawing, in which,—

Figure 1 is a perspective of a crate made 35 in accordance with my present invention.

Fig. 2 is a perspective of the bottom, sides and top extended before they are formed into a crate.

Fig. 3 is a fragmental section through the 40 laterally disposed laminated edges at the corner of the crate.

Fig. 4 is a section on line 4—4 of Fig. 3, and

Fig. 5 is a section on line 5—5 of Fig. 3. 45 The sides, bottom and top of my crate are each preferably formed of three longitudinally disposed spaced bars, 6, 7 and 8, and extending transversely across which are the slats, 9, 10, 11, 12 and 13. It will of course 50 be understood that a greater or less number of the longitudinal bars and transverse slats may be employed in accordance with the dimensions desired in the crate, or that the sections may be made continuous without the 55 openings formed by the spaced slats. Secured upon either end edge of each section

formed of the longitudinal members, 6, 7 and 8, and the transverse members, 9, 10, 11, 12 and 13, are laterally extended pieces, each formed of three layers of veneered strips secured together by nails or brads or in any other suitable manner. The ends of the outside and inside layers, 14 and 16, are beveled or mitered at a suitable angle, so as to properly assemble when the sides are formed into 60 a crate. The intermediate layer is not continuous but is preferably made of short lengths, 15^a, 15^b and 15^c, which are spaced from each other so as to provide pockets, 15, between the layers, 14 and 16, for the reception of the cross cleats of the end sections to be hereafter described. By reference to Fig. 2 it will be seen that the block, 15^c, is left rectangular and extends between and beyond the beveled edges of the pieces, 14 and 16, while at the opposite end no block is provided, so that the blocks 15^c, serve as tongues or tenons for the adjacent section. The end sections preferably consist of the vertical slats, 17, 18 and 19, secured to the horizontal 70 battens, 20 and 21. The ends of the battens, 20 and 21, are adapted to fit into the slots provided by spacing the intermediate pieces, 15^a, 15^b and 15^c, of the laterally extending edge, and the slats, 17, 18 and 19, preferably 75 abut the inner faces of the laminated lateral extensions upon the top and bottom section.

The bottom, top and sides are flexibly secured together by the wires, 22 and 23, secured to the respective sections by the staples, 24, or in any other suitable way. The friction developed by the insertion of the battens, 20 and 21, in the pockets of the laminated lateral extensions upon the sides 80 is usually ample to hold the crate together while the same is being packed, but nails or brads may be nailed through the laminated extensions at the points where they receive the tenons of adjacent sections or 85 where they receive the ends of the battens, 20 or 21, for greater security. Such nails preferably should be slightly longer than the thickness of the lateral extensions so as to facilitate their removal. After the crate 90 is properly packed, the cover is closed down, the ends of the wires, 22 and 23, are twisted together, which secures the crate in a sufficiently substantial manner to render it available for the extremely severe service required in shipping package freight. In 95 order to open the crate it is only necessary to 100 105 110

untwist the ends of the wires, 22 and 23, when the cover may be raised and after the crate has been emptied, the end pieces may be removed and folded between the bottom, 5 top and sides in a single comparatively flat package of much reduced size.

From the foregoing description taken in connection with the drawings, it is obvious that I provide an extremely strong and serv- 10 iceable crate which may be manufactured at a minimum cost and which has all the advantages of the hitherto known more expensive structures.

What I claim as new is:

- 15 1. A folding crate comprising bottom top and side sections each end edge of each section provided with a lateral extension formed of three layers of veneer the intermediate layer whereof is formed of spaced 20 strips whereby pockets and tenons are formed in said lateral extensions, means for flexibly securing said sections together, and end sections having projections thereon adapted to enter the pockets in said lateral 25 extensions.
2. A folding crate comprising bottom top and side sections each end edge of each section provided with a lateral extension hav-

ing mitered ends and formed of three layers of veneer the intermediate layer whereof is 30 formed of spaced strips whereby pockets and tenons are formed in said lateral exten- sions, means for flexibly securing said sec- tions together, and end sections having pro- 35 jections thereon adapted to enter the pock- ets in said lateral extensions.

3. A folding crate comprising bottom top and side sections each formed of longitudi- 40 nal spaced strips and transversely spaced strips of veneer and each end edge of each section provided with a lateral extension formed of three layers of veneer the inter- mediate layer whereof is formed of spaced strips whereby pockets and tenons are 45 formed in said lateral extensions, means for flexibly securing said sections together, and end sections having projections thereon adapted to enter the pockets in said lateral extensions.

Signed at Chicago, county of Cook and 50 State of Illinois, this 1st day of Sept., 1916.

CHARLES Q. C. LEIGH.
